RING ROLLING MILL

Erhard Henschker and Frank Sidney Salter,
Parkstone, England, assignors to The Loewy
Engineering Company Limited, London, Eng-
land, a corporation of Great Britain

Application July 23, 1949, Serial No. 106,438
In Great Britain February 24, 1947

10 Claims. (Cl. 80—5)

1

The invention relates to rolling mills in which rings are formed by reducing annular blanks between externally- and internally-acting rolls. In vertical rolling mills of this type, that end (hereafter called "the outboard end") over which the blanks were slid into rolling position and the finish rolled rings withdrawn, had to be left entirely unsupported. It was therefore not possible to use these rolling mills for working blanks with pre-formed holes of small diameter and requiring for their working internally-acting rolls of correspondingly small diameter, as such slender rolls, when left unsupported at one end were bound to be subjected to excessive deflections and internal stresses as soon as the full rolling pressure was applied.

For these reasons, vertical ring rolling mills were unsuitable for carrying out certain classes of work.

It is an object of the present invention to provide novel and improved means for supporting the internally-acting rolls of ring rolling mills, in particular, vertical ring rolling mills.

According to the present invention, the internally-acting roll of a ring rolling mill has a bearing at its outboard end, which bearing is mounted in a carrier capable of two separate movements, one parallel to the axis of the roll, and the other away from that axis. In this way, the bearing will be first stripped from its seat on the outboard end of the internally-acting roll and can then be readily withdrawn into a position sufficiently remote from the internally-acting roll to allow the blanks and finished rolled rings to be placed over and withdrawn from the internally-acting roll.

In one form of the invention, the carrier may be in the form of a cantilever arm projecting radially from a pillar to which it is connected or with which it forms a part, the arm being rotatable about the axis of the pillar and the pillar displaceable with the arm in a direction parallel to the axis of the internally-acting roll.

In vertical ring rolling mills, the rolling pressure is usually applied to the blanks through the intermediary of the internally-acting roll which is, therefore, often called also "the pressure roll," and this roll is, for this purpose, mounted on a slide which can be advanced towards the externally-acting roll by hydraulic or other means which supply the rolling pressure.

The supporting means for the outboard bearing provided according to the invention will then also be mounted on that slide. Means may be further provided for transmitting a predeter-

mined portion of the rolling pressure from the hydraulic or other means direct to the outboard bearing so as to ensure that this bearing receives no more than its due share of the total rolling pressure. These means may comprise a fulcrumed lever which receives the full rolling pressure and splits it up into two portions, of which one is directly transmitted to the outboard bearing. This arrangement facilitates also the computation of the individual loads on the other bearing of the internally-acting roll, as well as that of the bending moments.

As explained above, the invention has been devised in connection with rolling mills having internally-acting rolls of small or very small diameter. In slender rolls, the area available for the seat of the outboard bearing may not be sufficiently large for transmitting a proper share of the rolling pressure, and it is, therefore, a further feature of the invention to provide means by which this area is increased. These means may consist of a sleeve fitted over and clamped firmly on to the outboard end of the internally-acting roll, so as to rotate therewith, the sleeve being adapted to be placed on and withdrawn from its seat on the roll together with the outboard bearing. The sleeve may be suspended inside the bearing so as to be freely rotatable relative thereto.

The invention will now be described more in detail with reference to the accompanying drawings, in which several embodiments of ring rolling mills according to the invention are shown:

Fig. 1 is a sectional elevation through a vertical ring rolling mill according to the invention.

Fig. 2 is a detail view of a modified type of outboard bearing used in the mill according to Fig. 1.

Figs. 3 and 4 are detail views showing modifications of the pressure-transmitting means used in a rolling mill according to Fig. 1.

The rolling mill shown in the drawings is of the vertical type and has an externally-acting roll 10 and an internally-acting roll 11 which co-operate with each other in the reduction of thick-walled annular blanks B to thin-walled rings of correspondingly increased diameter.

The rolling pressure is transmitted to the blanks through the intermediary of the internally-acting roll 11, also called "the pressure roll." To this end, this roll is mounted on a slide 12 displaceable in the stationary frame 13 of the mill in a direction towards and away from the externally-acting roll 10 by means of a hydraulic ram 14 displaceable in a cylinder 15 which supplies the rolling pressure. Return movement of

the slide 12 is effected by means of the ram 14' displaceable in the cylinder 15'.

The torque required for the rolling is supplied to a spindle 16 carrying the externally-acting roll 10 from a source of power, not shown, through a pair of bevel gears 17, the spindle 16 being supported in the stationary frame 13.

The pressure roll 11 is connected through the intermediary of another pair of bevel gears 18 and a spindle 19 to an auxiliary power drive to start and maintain rotation of the pressure roll independently of the externally-acting roll, the drive comprising a motor 20, a reduction gear 21 and a slipping clutch 22.

As will be readily apparent from Fig. 1, the blanks B have to be slid over the outboard end of the pressure roll in order to be placed in a position ready for rolling, and the finish-rolled rings have to be removed from the pressure roll in the same way. The outboard end of the pressure roll has, therefore, to be free from any obstructions while workpieces are charged into or discharged from the rolling mill. To achieve this result, while at the same time providing a support for the outboard end of the pressure roll 11, an outboard bearing 23 is provided which is mounted on a retractable carrier 24 capable of two movements, one parallel to the axis of the pressure roll and the other one away from this axis, the latter movement being here a rotation about an axis parallel to that of the roll. The carrier 24 comprises, in the embodiment shown, a cantilever arm radially projecting from a pillar 25 which is adapted to be lifted and lowered by hydraulic cylinder 26 and ram 27, both arranged in the slide 12.

In Fig. 1, the outboard bearing 23 is shown as being situated on the outboard end of the pressure roll 11 after a blank B has been placed over this roll, and the slide 12 as having been advanced so as to approach the pressure roll to the externally acting roll. The outer end of the cantilever arm 24 has an extension 28 which, in the position shown in Fig. 1, is received in a socket 29 on the frame 13, so that the cantilever arm will serve as a brace for the outboard bearing 23.

The pillar 25 is journalled in the slide 12, so as to be readily rotatable therein after the outboard bearing has been lifted from its seat on the pressure roll. A comparatively small force will be sufficient to swing the cantilever arm 24 about the axis of the pillar 25, so that this movement can be effected by hand.

The lower end of the pressure roll 11, which is tapered, is drawn firmly into a conical recess on the top of the spindle 19 by means of a threaded coupling rod 30, whereby the pressure roll is firmly, but at the same time detachably, secured to the spindle 19 so as to be rotatable therewith.

The outboard bearing 23 is shown in Fig. 1, as comprising a sleeve 31 which is fitted over and clamped to the outboard end of the pressure roll 11 every time the bearing 23 is placed in position on that roll, the sleeve being suspended inside the outboard bearing so as to be freely rotatable therein. The rolling pressure will then be transmitted to the pressure roll at the outer surface of the sleeve 31, whereby it is possible to provide a sufficiently large area for the transmission of this pressure, independently of the diameter of the pressure roll, which, as stated above, is governed by the minimum diameter of the preformed holes in the blanks. The sleeve

31 is clamped to the pressure roll by means of a cup-shaped coupling piece 32 which is pressed against the conical end of the roll by a spring 33, the sleeve having ears 34 engaging with recesses in the sleeve 31 so as to couple these parts with each other for rotation. The sleeve is threaded to a cap 35 which forms an abutment for the spring 33.

Alternatively, the outboard bearing may comprise a standard type roller bearing 36, for example, as shown in Fig. 2. This bearing is axially held between the flanges of a housing 37 and of a sleeve 38 by means of a spring 39. The housing 37 is mounted on the cantilever arm 24 by means of keys, not shown here, which give the bearing assembly freedom of radial movement relative to the pressure roll 11.

The outboard bearing, especially if it is of the roller type, will have to be of restricted size in view of the small diameter of the pressure roll and can therefore transmit only a limited share of the rolling pressure. To prevent the bearing from being overloaded, means are preferably provided to ensure that only a predetermined portion of the rolling pressure is transmitted to the outboard bearing. As shown in Fig. 3, these means may comprise a lever 40 fulcrumed to the slide 12 by a pin 41 and engaged at a point near its fulcrum by a block 42 which in turn is connected to the ram 14 by means of tie-bars 43 and crosshead 44. Interposed between outboard bearing 23 and the lever 40 is a rod 45 which is slidable in the cantilever arm 24 and the pillar 25. The rod 45 abuts against the lever 40 at a point remote from the fulcrum pin 41, so that only a small proportion of the rolling pressure will be transmitted to the outboard bearing. It is, however, possible, and within the scope of the invention, to vary the proportion of the load received by the outboard bearing by varying the distances of the rod 45 and the block 40 from the pivot pin 41.

A buffer spring 46 is placed before the block 42 in order to keep the pressure roll 11 in engagement with the blanks B during the rolling process should one of the blanks have an uneven wall thickness due to eccentric piercing of the hole in the blank.

A modification of the pressure-transmitting means for the outboard bearing is shown in Fig. 4. In this case, the rod 45 is dispensed with and the cantilever arm 24 itself takes its place. The arm is then slidable in a tubular guide 47 radially extending from the top of the pillar 25 and it will be engaged by the lever 40 at the end remote from the outboard bearing.

It will be seen from the foregoing that the invention provides a ring rolling mill in which the internally-acting or pressure roll is fully supported at both its ends during the rolling operation so that the deflection and the stresses to which this roll is subjected by the rolling process will be kept at a minimum, while at the same time the free accessibility of this roll at its outboard end for work-charging and discharging purposes is maintained.

It is also evident that the invention provides means for determining exactly the share of the rolling pressure received by the outboard bearing, whereby any overloading of this bearing is effectively prevented.

By mounting the outboard bearing on a retractable carrier which is capable of two movements, one parallel to the axis of the pressure roll and one away from this axis, it will be en-

sured that the bearing can be withdrawn into any desired position, while, at the same time, the effective area of the bearing can be made to suit any requirements.

What we claim is:

1. In a ring rolling machine having external and internal rolls adapted to reduce annular blanks, the combination including an external roll carrying frame, a slide movable toward and away from an external roll on said frame during rolling, said slide having bearing means supporting one end of an internal roll, an arm mounted on said slide having bearing means for supporting the other end of said internal roll so that said internal roll and its bearings can move with said slide, and arm shifting means on said slide and connected with said arm moving said arm in a direction parallel with the axis of said bearing means on the slide toward and away from an internal roll on said slide and independent thereof.

2. In a ring rolling machine having external and internal rolls adapted to reduce annular blanks, the combination including an external roll carrying frame, a slide movable toward and away from an external roll on said frame during rolling, said slide having bearing means adapted to support one end of an internal roll, an arm mounted on said slide having bearing means for supporting the other end of said internal roll, said bearing means on said slide being movable therewith, and power operated arm shifting mechanism mounted on said slide and connected with said arm moving said arm and its bearing means for said internal roll toward and away from an internal roll on said slide in a direction parallel to the axis of said bearing and internal roll.

3. In a ring rolling machine having external and internal rolls adapted to reduce annular blanks, the combination including a stationary external roll carrying frame, a slide movable toward and away from an external roll on said frame during rolling, said slide having bearing means adapted to support one end of an internal roll, said bearing on the slide being movable therewith, an arm having one end supported in said slide, a bearing supported adjacent the other end of said arm adapted to hold the opposite end of said internal roll, and power operated arm shifting mechanism mounted on said slide and connected with said arm moving said arm and its bearing for said internal roll toward and away from an internal roll on said slide in a direction parallel to the axis of said bearing and internal roll.

4. In a ring rolling machine having external and internal rolls adapted to reduce annular blanks, the combination including an external roll carrying frame, a slide movable toward and away from an external roll on said frame, said slide having means adapted to support one end of an internal roll, a pillar on said slide, a cantilever arm supported on said pillar, means mounted on said arm for supporting the other end of said internal roll, and power operated arm shifting mechanism mounted on said slide and connected with said arm moving said arm toward and away from an internal roll on said slide in a direction substantially parallel to the axis of said bearing and internal roll.

5. In a ring rolling machine having external and internal rolls adapted to reduce annular blanks, the combination including a stationary

external roll carrying frame, a slide movable in a horizontal direction toward and away from an external roll on said frame during rolling, said slide having bearing means rotatably supporting one end of an internal roll, said bearing means on the slide being movable therewith,

5 5. In a ring rolling machine having external and internal rolls adapted to reduce annular blanks, the combination including an external roll carrying frame, a slide movable toward and away from an external roll on said frame, said slide having bearing means adapted to support one end of an internal roll, a pillar mounted on said slide, a cantilever arm rotatably mounted in said pillar, a bearing carried by said arm for the other 10 end of said internal roll, and power operated arm shifting mechanism mounted on said slide and connected with said arm moving said arm and its bearing toward and away from an internal roll on said slide and independent thereof.

15 6. In a ring rolling machine having external and internal rolls adapted to reduce annular blanks, the combination including an external roll carrying frame, a slide movable toward and away from an external roll on said frame, said slide having bearing means adapted to support one end of an internal roll, a pillar mounted on said slide, a cantilever arm rotatably mounted in said pillar, a bearing carried by said arm for the other 20 end of said internal roll, and power operated arm shifting mechanism mounted on said slide and connected with said arm moving said arm and its bearing toward and away from an internal roll on said slide and independent thereof.

25 7. In a ring rolling machine having external and internal rolls adapted to reduce annular blanks, the combination including an external roll carrying frame, a slide movable toward and away from an external roll on said frame, said slide having bearing means including a bearing adapted to support one end of an internal roll, a hollow driving spindle in said slide for supporting the other end of said internal roll, coupling means extending through said hollow spindle attachable to said internal roll for holding it in place on the slide, and power operated arm shifting mechanism mounted on said slide and connected with said arm moving said arm and its bearing toward and away from an internal roll on said slide in a direction substantially parallel to the axis of the internal roll on the slide.

30 8. In a ring rolling machine having external and internal rolls adapted to reduce annular blanks, the combination including an external roll carrying frame, a slide movable toward and away from an external roll on said frame during rolling, said slide having bearing means adapted 35 to support one end of an internal roll, an arm rotatably mounted on said slide and movable therewith, a bearing mounted on said arm for supporting the opposite end of said internal roll, a sleeve mounted in said bearing on said arm freely rotatable relative to said bearing and axially movable relative thereto, means connecting said sleeve to said internal roll for rotation therewith, and power operated arm shifting mechanism mounted on said slide and connected with said arm moving said arm and its bearing toward and away from an internal roll on said slide in a direction parallel to the axis of the internal roll on the slide.

35 9. In a ring rolling machine having external and internal rolls adapted to reduce annular blanks, the combination including an external roll carrying frame, a slide movable toward and away from an external roll on said frame, said slide having bearing means supporting one end of an internal roll, an arm mounted on said slide hav-

ing bearing means for supporting the other end of said internal roll, arm shifting means on said slide connected with said arm moving said arm in a direction substantially parallel with the axis of said bearing and independent of said roll, means applying rolling pressure to said slide tending to move said rolls together, and means applying a predetermined portion of said rolling pressure direct to said bearing.

10. In a ring rolling machine having external and internal rolls adapted to reduce annular blanks, the combination including an external roll carrying frame, a slide movable toward and away from an external roll on said frame, said slide having means supporting one end of an internal roll, an arm mounted on said slide having bearing means for supporting the other end of said internal roll, arm shifting means on said slide connected with said arm moving said arm in a direction substantially parallel with the axis 15 of said bearing and independent of said roll, means applying rolling pressure to said slide tending to move said rolls together, and means applying a predetermined portion of said rolling pressure direct to said bearing.

5

means applying rolling pressure to said slide tending to move said rolls together, fulcrum lever means receiving said rolling pressure, and a thrust member connecting said fulcrum lever with said bearing so as to apply a part of the rolling pressure directly to said bearing.
